(74) Attorney, Agent, or Firm — Wayne & Ken, LLC;
Tony Hom(57) CLAIM

The ornamental design for ground cleaning device, as shown and described.

DESCRIPTION

FIG. 1 is a perspective view of ground cleaning device showing my new design;

FIG. 2 is another perspective view thereof;

FIG. 3 is a front elevation view thereof;

FIG. 4 is a back elevation view thereof;

FIG. 5 is a left side view thereof;

FIG. 6 is a right side view thereof;

FIG. 7 is a top plan view thereof; and,

FIG. 8 is a bottom plan view thereof.

The broken lines in the drawing depict environmental subject matter only and form no part of the claimed design.
